CARBURETOR

Richard W. Engnath, Brooklyn, N. Y.

Application October 30, 1940, Serial No. 363,400

4 Claims. (Cl. 261—47)

The present invention relates to new and useful improvements in fuel carburetors for internal combustion engines, and more particularly to improved carburetors for volatile liquid fuels for automotive vehicles.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a side elevation of a typical and illustrative embodiment of the present invention;

Figure 2 is a horizontal sectional view taken on the line 2—2 of Figure 1;

Figure 3 is a fragmentary vertical sectional view taken on the line 3—3 of Figure 2;

Figure 4 is a fragmentary detailed sectional view taken on the line 4—4 of Figure 3;

Figure 5 is a vertical sectional view taken on the line 5—5 of Figure 2;

Figure 6 is a vertical sectional view taken on the line 6—6 of Figure 1;

Figure 7 is a fragmentary sectional view taken on the line 7—7 of Figure 5 and showing the valve in closed position;

Figure 8 is a similar sectional view showing the valve in its open position;

Figure 9 is a detailed side elevation, with a part broken away and showing the outer portion of the valve of Figures 7 and 8; and

Figure 10 is a similar view of the internal portion of the valve shown in Figures 7 and 8.

The present invention has for its object the provision of a novel and improved carburetor for volatile liquid motor fuels particularly for use with internal combustion engines. The invention also provides an improved carburetor in which substantially complete volatilization of the liquid motor fuel is produced before the fuel is introduced into the intake of the internal combustion engine. Another object of the invention is the provision of a carburetor in which an accurately regulable amount of a rich fuel-air mixture is fed to a larger quantity of air in the intake to form the explosive intake mixture for the engine. The invention also provides a carburetor having a plurality of premixing chambers which are regulably connected to the intake to supply the correct fuel-air mixture to the engine. The

invention has for another object the provision of a carburetor in which a throttled, substantially saturated fuel-air mixture is fed to the intake and mixed with air to be fed to the engine. The invention has for still another object the provision of an improved carburetor which is not liable to become clogged with dirt or foreign material, which effects substantial fuel economies in the running of the engine, and efficiently produces a fuel-air mixture for combustion in the engine at all operating conditions of the engine.

Referring now in detail to the present and preferred embodiment of the invention as illustrated in the accompanying sheets of drawings, the intake comprises a generally vertically extending tube 10 of a diameter sufficient for the volumetric capacity of the engine with which it is to be used. Air is admitted to the intake at its lower end 11 and after being mixed with vaporized fuel is fed to the engine from the upper end 12 of the intake tube 10.

Intermediate the ends of the tube 10 is provided the throttle valve 15 of substantially conventional construction which is mounted for rotation on a shaft 16 connected with the accelerator pedal or other control member (not shown), and this valve 15 may be rotated in the direction of the arrow (Figure 6) to move it to open position to increase the power of the engine, by increasing the volume of air passing through the manifold.

Below the throttle valve 15 is provided another valve which is normally substantially closed and is opened by the suction of the air drawn by the engine through the manifold 10 against the tension of springs. This valve may comprise the pair of pivoted leaves 17 mounted on their shafts 18 in the side walls of the lower portion of the tube 10. The leaves 17 preferably have fairly close contact at their sides with the parallel walls 19 of the valve chamber 20. Each of the valve leaves 17 is formed with a downwardly depending lug 21 to which is connected the upper end of a coil spring 23, the lower ends of springs 23 being connected to a yoke 24 which is adjustably supported by means of the locked screw 25 threaded into the lower elbow portion of the tube end 11.

With the engine idling, the leaves 17 are substantially closed (Figure 6) and the major portion of the air passing through the intake is introduced through air filter 51 and tube 50. As the throttle is opened, the suction is increased on the upper surface of the leaves 17 so that they are swung open against the tension of the springs 23 a sufficient amount to allow the proper quantity of air to pass into the tube 10.

Adjacent the manifold is maintained a small reservoir of fuel and for this purpose there is provided a float chamber 30 which is preferably vented to the atmosphere as by the vent port

86, Fig. 5, into which fuel is delivered from the main fuel supply through the fuel pipe 31 under control of the float 32 which regulates the level of the fuel in the reservoir to maintain it constant in the usual manner by means of a valve (not shown) controlled by the float. The reservoir is formed with a plurality of small depressions 33, of which three are shown, into each of which are threaded the combined fuel jets and induction tubes, the depressions serving to catch any foreign particles, water, etc., which might otherwise be fed into the jets and might clog the jets or otherwise interfere with the running of the engine.

Also adjacent the intake manifold and connected therewith are a plurality of premixing chambers 40 and 41 of substantial volume into which atomized fuel is sprayed with a substantial amount of air to produce a rich and partially saturated fuel-air mixture which is sucked into the intake tube 10 to be mixed with additional air and be fed to the engine. Premixing chamber 40 is normally disconnected from chamber 41 by means of the valve 43 which normally covers the intercommunicating aperture 46 and is lightly held in closed position by means of the coil spring 44 and stud 45, so that the valve may be opened whenever there is a slightly greater pressure of air within the chamber 40 than in the chamber 41.

Chambers 40 and 41 are connected with the intake tube 10, as will be further described in detail, and during the running of the engine there is a reduced pressure in each of them. The rich air-fuel mixture is supplied to chamber 40 by means of the induction tube 50 which is threaded into an aperture in the bottom of depression 33 and extends up into and fills an alined aperture in the bottom of the chamber 40. Tube 50 may be provided with an air-filter 51 at its lower end, but is otherwise unobstructed, or the air-filter may be omitted and the lower end of tube 50 connected directly to the lower end 11 of the manifold. Within the tube 50 is a concentric smaller tube 53 providing a space for the passage of air between the tubes 50 and 53. The upper end of tube 53 is provided with an atomizing jet 54 positioned slightly above the normal float level of the fuel in the reservoir 30, while the lower end of the tube 53 is bent and is tightly fitted into a suitable aperture in the side wall of the tube 50, the aperture being positioned well above the bottom of the reservoir so that fuel may be drawn into the tube 53 to be atomized through jet 54 due both to the velocity of air passing the jet 54 and to the slightly reduced pressure in the chamber 40.

In order to prevent liquid fuel accumulating in the chambers 40 and 41, in case an excess is atomized and not volatilized, drain holes 56 are formed in shallow depressions in the bottom walls of the chambers 40 and 41 so that any such unvolatilized fuel may be returned to the float chamber 30.

Chamber 41 is provided with a plurality of fuel atomizing tubes 60 each of which may be similar in construction to tube 50, are threaded into similar apertures in the depressions 33 and enter the chamber 41 through alined, tightly fitting apertures in the bottom wall 47 of the chamber 41, the wall 47 forming the separating partition between the chambers 40 and 41 and the reservoir 30. The upper portion of the cham-

bers 40 and 41 is closed by means of the plate 48 held by screws 49 so that it may be removed for cleaning, inspection, etc.

Rich fuel-air mixture is fed from the premixing chamber 40 to the intake tube 10 for idling of the engine through a relatively small conduit 65 which leads from the premixing chamber 40 to the tube 10 past a needle valve 66 serving to regulate the amount of this rich fuel-air mixture which is fed relative to the air introduced through the tube 10. A by-pass conduit 68 is connected with the conduit 65 and also leads to the tube 10, and is provided with a similar needle valve 69, and a small filter element 70 is interposed between the conduit 68 and the conduit 65.

Means are provided for variably controlling the communication of one of the premixing chambers with the intake tube in accordance with the opening of the throttle 15 so that as the throttle is opened, more of the rich fuel-air mixture may be fed from the premixing chamber to the intake tube to maintain a constant fuel-air ratio delivered to the engine. For this purpose, a valve is provided between the chamber 41 and the tube 10 and is adapted to be opened and closed proportionally to the throttle.

As embodied, the butterfly valve is provided with an upwardly projecting lug 73 which is connected by link 74 to an eccentric pin 78 on plate 79 forming the end of the rotatable inner member 80 of the valve between the chamber 41 and the tube 10. Valve member 80 is rotatable within the outer member 81 which is threaded into an aperture between the chamber and tube, and the members 81 and 80 are provided with registering apertures 82 which are closed by relative rotation of the parts. Inner member 80 is provided with an annular groove 83 into which projects the end of a screw 85 serving to hold the members against relative axial movement and the link 74 and other parts are so proportioned and positioned that with the butterfly valve 15 closed, the apertures 82 in the valve are closed, and the valve is gradually opened proportionally to the opening of the throttle 15, assuming its fully open position when the throttle 15 is fully open. The valve member 81 is hollow and opens directly into the chamber 41, so that when it is open the maximum amount of rich fuel-air mixture is delivered from the chamber 41 to the tube 10 and the maximum amount of air passes through the tubes 60 to increase the amount of atomized fuel delivered to the premixing chamber 41 for volatilization.

When the throttle 15 is opened quickly, the pressure within the chamber 41 is suddenly reduced and the pressure difference between the chambers 40 and 41 causes valve member 43 to be lifted from the aperture 46 so that an additional amount of rich fuel-air mixture may be delivered to the tube 10 through the valve apertures 82.

The operation of the described embodiment may be summarized as follows:

During the idling operation of the engine, air passes through the intake tube 10 under considerable suction and is delivered to the engine. This suction in the tube may lift the valve leaves 47 very slightly to permit the entry of this air, but the suction is principally communicated through the conduit 65 to cause air to be drawn through the tube 50 past the nozzle 54 and due to the reduced pressure and the induced suction,

fuel is atomized by the jet 54 into the chamber 40, the fuel level always being maintained in the reservoir 30 by fresh fuel delivered through the supply pipe 31. The atomized fuel is vaporized in the chamber 40, any unvaporized drops collecting on the walls of the chamber and being eventually returned to the reservoir 30 through the aperture 56, and the chamber 40 is thereby filled with a relatively large volume of air to form the combustible or explosive mixture.

The rich fuel-air mixture from the premixing chamber 40 is fed (for idling) through the conduit 65 to the intake tube and when diluted by the air in the tube forms the homogeneous explosive fuel-air mixture for the engine. Also, some of this mixture is passed through screen 70 to remove all unvaporized fuel and to provide an additional supply of fuel-air mixture to the tube through conduit 68, which is controlled by needle valve 69.

When the engine is operating under load and with the throttle 15 partially or fully open, the fuel-air valve 80, 81 is open to a corresponding degree and rich fuel-air mixture is delivered from the premixing chamber 41 to the intake tube 10 through the apertures 82, the amount of the fuel-air mixture being properly metered by the degree of opening of the apertures 82. The rich fuel-air mixture in the chamber 41 is replenished by the suction and velocity action of the air drawn through the tubes 60 which atomize additional fuel through the jets 54 in these tubes 60 and deliver this atomized fuel to the chamber 41, any unvaporized fuel collecting and draining through the apertures 56 back into the reservoir 30. Thus again substantially saturated fuel-air mixtures is delivered to the tube 10 rather than the customary raw unvaporized spray of fuel.

When the throttle 15 is opened quickly, as for rapid acceleration in traffic, the pressure in premixing chamber 41 drops rapidly, the pressure in chamber 40 drops only slowly and the resulting difference in pressure causes the valve closure 43 to be opened allowing additional fuel-air mixture to be supplied to the tube 10 from both the chambers 40 and 41 thereby giving the increased richness which is needed for the heavier load imposed on the engine, and as soon as this pressure difference has been reduced the valve 43 closes so that the further supply of fuel to the engine is at the usual, relatively lean rate.

As will be seen from the foregoing detailed description of the illustrative embodiment of the invention and from the description of its operation, complete volatilization of the fuel supplied to the engine is assured, and because a completely gaseous mixture is being supplied to the manifold and mixture, greater homogeneity of the fuel-air mixture can be obtained and maintained than is possible where the fuel is directly atomized into the intake air. The rate at which fuel is supplied does not depend entirely, nor largely, upon the Venturi action of the various jets at different velocities, but rather the flow of fuel to the engine is primarily controlled by a metering valve which operates on a relatively rich and entirely gaseous fuel-air mixture.

The invention in its broader aspects is not limited to the specific mechanisms shown and described but departures may be made therefrom within the scope of the accompanying claims without departing from the principles of

the invention and without sacrificing its chief advantages.

What I claim is:

1. In a carburetor for internal combustion engines the combination of an air intake passage having an air throttle valve therein, a plurality of premixing chambers connected to the intake passage, a small duct forming the connection from one of said chambers to the intake passage, a variable valve forming the connection from another of said chambers to the intake passage down-stream of the throttle valve, a suction operated valve interconnecting the chambers to connect one to the other when the throttle valve is suddenly opened, means interconnecting the variable valve to the throttle valve to open the variable valve as the throttle valve is opened, a fuel reservoir, air tubes each having an atomizing jet fed by the reservoir for introducing fuel and air into the premixing chambers and means for returning unvolatilized fuel from the premixing chambers to the reservoir.
2. In a carburetor for internal combustion engines the combination of an air intake passage having an air throttle valve therein, a plurality of premixing chambers connected to the intake passage, a small duct forming the connection from one of said chambers to the intake passage, a variable valve forming the connection from another of said chambers to the intake passage down-stream of the throttle valve, a suction operated valve interconnecting the chambers to connect one to the other when the throttle is suddenly opened, means interconnecting the variable valve to the throttle valve to open the variable valve as the throttle valve is opened, a fuel reservoir, and an atomizing jet fed by the reservoir for introducing fuel and air into the premixing chambers.
3. In a carburetor for internal combustion engines, the combination of an air intake passage having an air throttle valve therein, a plurality of premixing chambers connected to the intake passage, a small duct forming the connection from one of said chambers to the intake passage, a variable valve forming a connection from another of said chambers to the intake passage down-stream of said throttle valve, a suction operated valve interconnecting the chambers, means to open the variable valve as the throttle valve is opened, a fuel reservoir and air tubes each having an atomizing jet fed by the reservoir for introducing fuel and air into the premixing chambers.
4. In a carburetor for internal combustion engines, the combination of an air intake passage having a variable area inlet, an air throttle valve in said intake passage, a plurality of premixing chambers connected to the intake passage, a small idling duct forming the connection from one of said chambers to the intake passage, a variable valve forming a connection from another of said chambers to the intake passage down-stream of said throttle valve, a suction operated valve interconnecting the chambers, means to open the variable valve as the throttle valve is opened, a fuel reservoir, and an atomizing jet fed by the reservoir for introducing fuel and air into the premixing chambers.

RICHARD W. ENGNATH.
